ANDREW GEORGE HUTCHINSON, OF STONEYCROFT, NEAR LIVERPOOL, GREAT BRITAIN,
ASSIGNOR TO THOMAS ROWLAND AND HENRY ROWLAND.

Letters Patent No. 92,610, dated July 13, 1869.

IMPROVED BURGLAR-ALARM.

The Schedule referred to in these Letters Patent and making part of the same.

To all whom it may concern:

Be it known that I, ANDREW GEORGE HUTCHINSON, of Stoneycroft, Liverpool, in the county of Lancaster, and Kingdom of Great Britain, have invented a Combined Burglar-Alarm and Door or Window-Fastening; and I do hereby declare that the following is a full, clear, and exact description thereof, reference being had to the accompanying drawings, making part of this specification, in which—

Figure 1 is a perspective view of the alarm applied to a door, ready to give a signal should an attempt be made to open the door.

Figure 2 is a section, taken through the instrument in the vertical plane indicated by the line *y y* in fig. 3.

Figure 3 is a horizontal section through the instrument, taken in the plane indicated by the line *x x* in fig. 2.

Similar letters of reference indicate corresponding parts in the several figures.

The object of the invention is to combine, in a very compact and portable instrument, a device which will offer resistance to the opening of doors and windows with mechanism which will produce an audible alarm or signal in the event of a burglarious attempt to open a door or window thus secured.

The nature of my invention consists—

First, in a movable wedge or inclined plane, formed on one end of a loaded lever, and provided with a device for latching it in a depressed position, in combination with alarm-mechanism, which, when it is wound up, will be set free by the depression of said wedge, as will be hereinafter explained.

Secondly, in providing the case or box, which contains the alarm-mechanism, with spikes on its bottom, which will catch into a floor, or other object, and serve, in conjunction with the movable-wedge fastening, to resist an attempt to open a door or window, as will be hereinafter explained.

To enable others skilled in the art to understand my invention, I will describe its construction and operation.

In the accompanying drawings—

A represents a case or box, which is closed at bottom and open at top, and which may be made of wrought sheet-metal or of cast-metal, of the cylindrical form shown.

C is a rectangular tube extending out a short distance from the side of the box *A*, at or near its bottom, and

B represents a bell, which is arranged just above the top of the box *A*, and supported upon the upper end of an upright rod *E*, to which rod the bell is secured, by means of a nut, *h*, by removing which and the bell *B*, access can be had to the interior of the box *A*.

The lower end of the bell-support *E* is bent, and fastened rigidly to the bottom of box *A*, so as to af-

ford a raised support for the frame of the alarm-mechanism. The other support for this frame is a bar, *P*, having right angle pointed ends *P'*, which bar is secured fast to the bottom of box *A*, inside thereof, and its pointed ends protruded through the said bottom, so as to form holding-spikes, for preventing the instrument from slipping when arranged for operation.

The frame *F* is held down in place upon its supports by means of a hook, *n*, on the outer end of which a nut, *N*, is screwed tightly against the external surface of the box *A*.

This frame affords bearings for shafts carrying a train of wheels, and a spring, which latter is upon the winding-up-shaft, the key *K* of which is passed through a hole made through the box *A*, as indicated in fig. 3.

The escapement-wheel *G* is acted upon by vibrating pallets *H*, moving on an arbor, and carrying the hammer *J* and a release-rod, *g*.

The hammer *J* is arranged so as to strike the bell *B*, and the release-rod *g* is bent, and is so arranged that a portion of it will be beneath the inner loaded end of a lever, *D*, when this lever is in position indicated by black lines, fig. 2.

The lever *D* is pivoted to the tubular portion *C*, at *d*, and on its front end a wedge, *D'*, is formed, which inclines from the upper termination of tube *C* to a point which is at or near the lower termination thereof. This lever *D* has a gravitating latch, *a*, pivoted to it at *d*, the bevelled nose of which plays through a slot made through the top of tube *C*, and when the wedge-end or shortest arm of the lever *D* is pressed down fully, this bevelled nose will catch on one edge of the tube surrounding the said slot, as indicated in red lines, fig. 2, thereby holding up the loaded end of the lever, and releasing the escapement.

The following is a description of the manner of applying the improved instrument to a door:

The door is shut, and after the striking-mechanism is wound up, and the loaded end of the lever depressed, the bevelled portion *D'* is adjusted between the bottom edge of the door and the sill or floor, and, by a slight pressure upon case *A*, the spikes *P' P'* will penetrate the floor, and offer resistance to the opening of the door.

When the instrument is thus arranged, an attempt to open the door will cause a depression of the front end of lever *D*, which will raise the rear or inner loaded end of this lever high enough to cause the latch to catch and hold it up, at the same time releasing the escapement of the striking-mechanism, and giving an alarm upon the bell *B*.

If it is desired to prevent the front end *D'* of the lever *D* from being casually depressed when the striking or alarm-mechanism is wound up, this may be done by a small eccentric or cam *b*, pivoted to the top of tube *C*, and provided with a thumb-button, *b'*.

This cam *b* is so arranged that, when it is turned, as indicated in black, fig. 2, it will press against the nose of latch *a*, and, by holding down this latch, prevent the alarm-mechanism from being casually started.

Having described my invention,

What I claim as new, and desire to secure by Letters Patent, is—

1. The combination of the pivoted lever *D*, catch *a*, and alarm, all substantially in the manner and for the purpose described.

2. The button *b* in combination with the catch *a*,

lever *D D'*, and the alarm, all substantially as herein specified.

3. A portable burglar's alarm, constructed substantially in the manner and for the purpose described.

Witness my hand in matter of my application for a patent for improvement in burglar-alarms.
